UNITED STATES PATENT OFFICE.

ANDREW MORRISON, OF PITTSBURGH, PENNSYLVANIA, ASSIGNOR TO DILWORTH, PORTER & COMPANY, LIMITED, OF PITTSBURGH, PENNSYLVANIA.

TIE-PLATE.

1,143,301.

Specification of Letters Patent. Patented June 15, 1915.

Application filed March 5, 1915. Serial No. 12,258.

To all whom it may concern:

Be it known that I, ANDREW MORRISON, a citizen of the United States, residing at Pittsburgh, in the county of Allegheny and State of Pennsylvania, have invented a new Improvement in Tie-Plates, of which the following is a full, clear, and exact description, reference being had to the accompanying drawings, forming part of this specification, in which—

Figure 1 is a cross sectional view showing one of my improved tie plates applied to a rail and tie, and Fig. 2 is a bottom plan view of the tie plate.

The object of my invention is to provide a tie plate which can be readily rolled, and which will seat and embed itself upon a wooden tie in a manner to afford a maximum lateral resistance to outward creeping, and which will at the same time be anti-cutting.

The nature of my invention will be best understood by reference to the accompanying drawing, in which I have shown the preferred form thereof and which will now be described, it being premised however that changes can be made in the precise form and shape of the parts of the plate without departing from the spirit and scope of my invention as defined in the appended claims.

The upper surface of the tie plate is formed with the intermediate rail seating surface at 2, terminating at one side at the base of the upwardly projecting longitudinal rib 3 against which the outer edge of a rail base 4 is adapted to abut. The upper surface of the edge portions of the plate are preferably beveled outwardly and downwardly, as indicated at 5. The upper surface of the plate may, however, be of any desired form or pattern.

On its under surface the tie plate is provided with a plurality of bearing projections 6 which extend from side to side of the plate and substantially parallel with the rail. The initial bearing surface of the projection 6 is preferably somewhat rounded or convex so as to be non-cutting in its action on a tie 7, and the outer side 8 of each projection is somewhat abrupt, while the inner side is formed by a sloping surface 9 which extends upwardly and inwardly, where it merges with the abrupt outer side of the adjacent projection; or

the bottom surface of the tie between adjacent projections 6 may be considered as composed of a series of plane surfaces which are at an angle to the rail bearing top surface of the plate and which slope upwardly and inwardly.

10 designates the usual holes for spikes 11. These holes may be arranged in any usual or suitable manner, and any desired number thereof may be provided in one or both edge portions of the plate. In general, the plate may be adapted for the use of any suitable fastening device.

The advantages of my invention arise from the peculiar construction of the under surface of the plate having the non-cutting projections extending from side to side with the intermediate upwardly and inwardly sloping plane surfaces. When the plate is initially seated upon the top of a tie it takes its bearing only on the projections 6. Under service, these projections gradually embed themselves in the tie, without, however, positively cutting the fiber of the tie. The abrupt outer sides 8 of the projections afford a maximum lateral resistance against spreading of the plate in the direction of the outside of the track.

While I have shown the preferred form of tie plate as having three of these transverse projections 6, I do not limit myself to this number, as a greater or less number may be employed. I do, however, consider it essential that there shall be at least one of these projections underneath the base of the rail. Where a plurality of the projections are employed, I prefer to place one of them directly below the rib or projection 3.

The construction of the tie plate is such as to enable it to be readily rolled in commercial mills, as will be apparent.

I claim:

1. A railway tie plate of generally rectangular form and having its greatest dimension in a direction at substantially right angles to the length of the rail which it supports, said plate being adapted to be seated on and secured to a single tie and having its under or tie-engaging surface formed with a transverse projection extending substantially parallel to the length of the rail, said projection extending from edge to edge of the plate and having a plane bearing surface which is inclined upwardly and inwardly toward the inner end of the

plate at an oblique angle to the upper rail bearing surface of the plate, substantially as described.

2. A railway tie plate of generally rectangular form and having its greatest dimension in a direction at substantially right angles to the length of the rail which it supports, said plate being adapted to be seated on and secured to a single tie and 10 having its under or tie-engaging surface formed with a transverse projection extending substantially parallel to the length of the rail, said projection extending from edge to edge of the plate and having a plane bearing surface which is inclined upwardly and inwardly toward the inner end of the plate at an oblique angle to the upper rail bearing surface of the plate, said projection being of rounded or convex form at its 15 highest point, substantially as described.

3. A railway tie plate of generally rec-

tangular form adapted to be seated and secured upon a single tie and having its greatest dimension at substantially right angles to the length of the rail which it seats, the 25 under surface of said plate having thereon a plurality of projections extending substantially parallel with the rail from edge to edge of the plate, each of said projections having a plane bearing surface which is inclined upwardly and inwardly toward the inner end of the plate at an oblique angle to the upper rail bearing surface of the plate and at least one of said projections being located under the rail-seating surface 30 of the plate, substantially as described.

In testimony whereof, I have hereunto set my hand.

ANDREW MORRISON.
